UNITED STATES PATENT OFFICE.

GEORGE HAMILTON SHRODES, OF LOS ANGELES, CALIFORNIA.

ARTIFICIAL LIMB.

Application filed March 29, 1926. Serial No. 98,103.

My invention relates to improvements in the lower portion of the leg and includes the foot and is specially found in the manner that the foot is connected to the leg. The object thereof is to produce simple and efficient parts which will function as do the natural parts which they replace and which, in case a part needs replacement, such repair may be done by an unskilled workman.

In the drawings forming a part of this application, Fig. 1 is a side elevation of my improved limb from the knee down. Fig. 2 is a side view of the foot and ankle portions of Fig. 1 with a portion of the foot and ankle in central vertical section. Fig. 3 is a top plan of the leg portion of Fig. 1, the foot portion being omitted. Figs. 4-5 and 6 are enlarged details (parts being in section) of the ankle portions.

Referring to the drawings, 10 is the top band. 11 and 12 are strengthening bands placed at suitable distances between the top band and the ankle casting 13. Casting 13 and bands 10-11 and 12 are connected by thin steel strips 14 which are united thereto by rivets or by other suitable means and together form the contour of the portion of the leg between the ankle and knee. The length and number of these strips and bands being determined by the shape of the limb that is replaced thereby. The most important part of my invention is in what I term the ankle joint. This joint is partly formed by casting 13 which is a hollow casting, the rear portion of which represents the os calcis or top of the heel and the front portion represents a portion of the astragalus or instep. The bottom 13^a of casting 13 is closed by a thin wall which has a transverse enlargement positioned centrally of the top of the casting. This enlargement is bored for the reception of a hollow bearing bolt 15, the bore of which is internally threaded at the ends for the reception of lag screws 16 which pass through the U shaped connector plate 17, thereby connecting plate 17 to bottom 13. The central portion of bolt 15 is preferably reduced in size to secure lightness and also to provide a chamber 18 around the same to hold a lubricant. A port 19 in bolt 15 connects the bore of the bolt with chamber 18 so that by taking out one of the lag screws the chamber can be filled with lu-

bricant. A foot member 20 made of any suitable material, preferably of light strong wood has a recess 21 in the rear portion thereof in the top of which is received the bottom of casting 13. Secured to member 20 within recess 21 is a curved leaf spring 22, the outer ends of which engage the bottom of casting 13 and normally hold the leg member at right angles to the plane that passes through the sole of the foot member. In the drawings, I have shown this spring made of two sections so that in case any part of the spring should break, a half leaf could be used to replace the broken part. Spring 22 is secured to the foot member by screws 23 and 24. Screws 24 also pass through plate 17 and secure it to the foot member. By this construction when the user places his heel on the ground in walking, the rear portion of spring 22 yields and no shock is produced. As he throws his body forward the front end of spring 22 yields, thus giving the foot member the same motion as is produced in the natural foot in walking.

The leg section has the conventional means to attach the same to the leg, the same not being shown as a part of my invention. The leg section has the knee bar 25 to which the attaching means is hingedly connected.

While I have shown the construction of leg member that I prefer, any other construction may be used providing it terminates in the upper part of my ankle construction.

Having described my invention, I claim—

1. The combination of a lower leg member with a foot member pivotally connected to the leg member for foot motion; and a curved leaf spring secured intermediate its ends to the foot member and having the ends detachably engaging the bottom of the leg member to normally hold the same at right angles to the plane of the sole of the foot member.

2. The combination of a lower leg member terminating in hollow casting, said casting having a configuration of the human ankle and having the bottom closed by a plate, said plate having a central transverse enlargement with a bore therethrough; a hollow bolt extending through said bore and having a reduced central portion with a port therein, said bolt being internally threaded at the ends; with a foot member

having a recess in the rear portion; a curved leaf spring secured to said foot portion, the ends of which engage the bottom of the leg casting and holds the leg member 5 at right angles to the plane of the sole, a U-shaped plate secured to said foot portion, the upper members of which are pierced,

and lag screws passing through said pierced ends and engaging in threaded contact with the bolt chambered in the casting.

In witness that I claim the foregoing I have hereunto subscribed my name this 18th day of March, 1926.

GEORGE HAMILTON SHRODES.
